UNITED STATES PATENT OFFICE

ANDREW P. WHITLOCK, OF LEBANON, TENNESSEE

BOOK

Application filed March 13, 1929. Serial No. 346,661.

This invention relates to books, and particularly to auxiliary leaves for books, one object of the invention being to provide a construction of auxiliary leaf sheet, and mode of applying the same to a book, whereby additional leaves are furnished before and after the main leaves at the front and back of the book, which auxiliary leaves may be used for advertising or other purposes.

10 A further object of the invention is to provide an auxiliary leaf sheet having a central binding portion and terminal fly leaf portions which may, respectively, be secured between the back portions of the main leaves 15 and back of the cover and to the front and rear cover members, so as to be firmly and securely retained in the book.

The invention consists of the features of construction, combination and arrangement 20 of parts, hereinafter fully described and claimed, reference being had to the accompanying drawings, in which:—

Fig. 1 is a perspective view of the auxiliary leaf sheet, showing the same in partly 25 outspread condition.

Fig. 2 is a view of the sheet, as it appears from the rear, and as inserted for application in the book.

Fig. 3 is a top plan view of the folded 30 sheet, showing the same in full lines, and indicating in dotted lines the relative positions of the main leaves and cover of the book, when the auxiliary leaves are applied.

The auxiliary leaves are preferably provided initially in the form of a single sheet 35 6, comprising a central portion or strip 7 and portions 8, 9, 10, 11, 12 and 13, at opposite sides thereof, foldable upon the lines 14, 15 and 16 and 17, 18 and 19 to provide front 40 and rear sets of leaves. The center portion or strip 7 constitutes a binder portion for the auxiliary sheet which is of the same general dimensions as the back or binding member of the book cover and, in the formation 45 of the book, and after the main leaves have been assembled, the part 7 is disposed and fastened between the cover back and backs of the main leaves, whereby the auxiliary leaf is centrally secured in the book at the time the 50 cover is applied. By this arrangement the

group of auxiliary leaf sections 8, 9 and 10 will be disposed between the main leaves and the front cover section of the book, while the group of auxiliary leaf sections 11, 12 and 13 will be disposed between the main leaves and the rear cover section of the book. The relatively inner faces of the terminal leaf sections 10 and 11 are then pasted or otherwise secured to the inner surfaces of the cover leaves of the book so as to take the place of the usual fly leaves. The book will then present a front set of auxiliary leaf portions 8, 9 and 10, in which the fold line 15 between the portions 8 and 9 is forwardly directed, and a rear set of leaf portions 11, 12 and 13 in which the fold line 18 between the leaf portions 11 and 12 is forwardly directed. The leaf sections 8 and 9 may be separated from each other along the line 15 and the leaf sections 11 and 12 along the line 18 during the 60 operation of trimming and cutting the edges of the main leaves 1, or the auxiliary leaves mentioned may be left intact along the said fold lines so as to be later separated by the user of the book. When division is made along the fold lines 15 and 18 the leaf sections 8 and 11 will be held united to the book, at the back thereof, while the leaf sections 9 and 10 and 12 and 13 will be secured by the leaf section 10 to the front cover section of 65 the book and by the leaf section 13 to the rear cover section of the book, so that all the auxiliary leaf sections will be firmly held in the book. When division is made along the fold lines 15 and 18 the leaf sections 8 and 11 will be held united to the book, at the back thereof, while the leaf sections 9 and 10 and 12 and 13 will be secured by the leaf section 10 to the front cover section of 70 the book and by the leaf section 13 to the rear cover section of the book, so that all the auxiliary leaf sections will be firmly held in the book. When division is made along the fold lines 15 and 18 the leaf sections 8 and 11 will be held united to the book, at the back thereof, while the leaf sections 9 and 10 and 12 and 13 will be secured by the leaf section 10 to the front cover section of 75 the book and by the leaf section 13 to the rear cover section of the book, so that all the auxiliary leaf sections will be firmly held in the book.

In practice, the obverse and reverse faces of all the auxiliary leaf sections may be provided with advertisements or other printed matter with the exception of the leaf sections 10 and 13, the outer or obverse faces only of which are printed for an obvious reason. The auxiliary sheets may constitute an advertising section of a book, and constitute a buyer's directory, or it may, if desired, be employed as an index section, or for any other purpose, the construction described enabling 80 an auxiliary advertising or other section to be made up and applied to a book, while the main leaf and cover portions of the latter are in process of assemblage, in a ready and convenient manner; and it is to be understood 85 95 100

that the auxiliary section may be employed as an auxiliary revenue producer or not, as desired by the publisher of the book. Of course the arrangement may be such that one or more of the free leaves 8, 9, 11, 12 is embodied in the form of a detachable premium coupon or order slip, if desired.

Having thus fully described my invention, I claim:-

- 10 1. An auxiliary sheet or signature for attachment to books having front and rear cover leaves and a back comprising a central binder section for attachment to a book back, and opposite groups of leaf sections at the sides thereof and integral therewith, each comprising at least three leaves united by fold lines on which the sheet has been folded alternately in opposite directions, all the leaves of each set being adapted to be printed upon both faces thereof except the rear faces of the outermost leaves, the latter being blank and adapted to be secured to the cover leaves.
- 15 2. An auxiliary sheet or signature for attachment to books having front and rear cover leaves and a back comprising a central binder section adapted to be bound in the back part of a book, end leaves adapted to be secured to the front and rear covers of the book, and intermediate leaves between each end leaf and the binder section forming with the end leaf a group of leaves united by fold lines on which the sheet has been alternately folded in opposite directions.
- 20 35 In testimony whereof I affix my signature.

ANDREW P. WHITLOCK.
